CLAIM

The ornamental design for beverage container holder, as shown and described.

DESCRIPTION

FIG. 1 is front elevation view of a beverage container holder showing our new design;

FIG. 2 is a back elevation view thereof.

FIG. 3 is a side elevation view thereof.

FIG. 4 is a top plan view thereof.

FIG. 5 is a bottom plan view thereof.

The side of the beverage container holder opposite from FIG. 3 is an identical mirror-image of FIG. 3.
